[57] CLAIM

The ornamental design for a data communications peripheral, as shown and described.

DESCRIPTION

FIG. 1 is a perspective view of a data communications peripheral showing our new design;

FIG. 2 is an enlarged top plan view thereof;

FIG. 3 is an enlarged front elevational view thereof;

FIG. 4 is an enlarged left side elevational view thereof;

FIG. 5 is an enlarged right side elevational view thereof;

FIG. 6 is an enlarged rear elevational view thereof;

FIG. 7 is an enlarged bottom plan view thereof;

FIG. 8 is an enlarged cross sectional view taken along line 8—8 of FIG. 2;

FIG. 9 is an enlarged cross sectional view taken along line 9—9 of FIG. 2;

FIG. 10 is a perspective view of a second embodiment of our design;

FIG. 11 is an enlarged top plan view thereof;

FIG. 12 is an enlarged front elevational view thereof;

FIG. 13 is an enlarged left side elevational view thereof;

FIG. 14 is an enlarged right side elevational view thereof;

FIG. 15 is an enlarged rear elevational view thereof;

FIG. 16 is an enlarged bottom plan view thereof;

FIG. 17 is an enlarged cross sectional view taken along line 17—17 of FIG. 11; and

FIG. 18 is an enlarged cross sectional view taken along line 18—18 of FIG. 11.

The circular pattern is understood to continue over the entire unshaded area in FIGS. 3, 4, 5, 7, 12, 13, 14 and 16.
